G. A. LAFONTAINE,
HAIR CLIPPER.
APPLICATION FILED APR. 3, 1919.

1,343,175.

Patented June 8, 1920.

UNITED STATES PATENT OFFICE.

GEORGE A. LAFONTAINE, OF SAN PEDRO, CALIFORNIA, ASSIGNOR OF ONE-HALF TO
OTTO STEINEN, OF LOS ANGELES, CALIFORNIA.

HAIR-CLIPPER.

1,343,175.

Specification of Letters Patent. Patented June 8, 1920.

Application filed April 3, 1919. Serial No. 288,862.

To all whom it may concern:

Be it known that I, GEORGE A. LAFONTAINE, a citizen of the United States, residing at San Pedro, in the county of Los Angeles and State of California, have invented new and useful Improvements in Hair-Clippers, of which the following is a specification.

This invention relates to hair clippers and particularly to a form of clippers adapted to be operated by power supplied from a motor or the like, and the primary object thereof is to provide an improved form of clippers having means for reciprocating the cutting blades and for applying power from an external source thereto.

A further object is to provide a clipper of the character referred to having a pair of relatively movable blades and means for supporting said blades in reversible relation to each other, so that the same may be turned for operation at right angles to or parallel with the handle.

Another object is to provide means for locking and firmly holding the cutting blades in a selected position when the same are moved to either of the positions referred to, and to provide means for removably holding all of the parts of the clippers together so that the mechanism may be readily disassembled for the purpose of cleaning or substituting new for worn parts. Other objects will appear as the description progresses.

In the drawings hereto annexed and forming a part of this application, I have shown a novel form and arrangement of parts constituting one practical embodiment of my invention, of which I will describe the operation and details in the specification hereinafter following.

In said drawings, in which similar characters of reference are employed for indicating the same or like parts:

Figure 1 is a plan of my assembled clippers;

Fig. 2 is a side elevation thereof;

Fig. 3 is a longitudinal section of the same on line 3-3 of Fig. 1;

Fig. 4 is a transverse section of the same on the line 4-4 of Fig. 1;

Fig. 5 is a perspective view of the stationary cutting blade;

Fig. 6 is a similar view of the movable blade;

Fig. 7 is a rear end view of the body on which the blades are mounted for operation;

Fig. 8 is a perspective view of the intermediate blade holding and spacing member; 60

Fig. 9 is a perspective view of the main body member;

Fig. 10 is a perspective view of the locking spring;

Fig. 11 is a perspective view of the locking member;

Fig. 12 is a composite perspective view of the cross head for moving the blade, together with the locking pin and driving elements for said cross head. 70

My improved mechanism comprises as main elements, a stationary blade S, a movable blade M, an intermediate holding and spacing member H, a primary body member B, a secondary body member b, a locking member L, a cross head C, and a driving element D, arranged and formed as clearly shown in the drawings and removably held together, the specific details and operation of which elements I will now describe. 80

Stationary blade S, as shown, has cutting teeth 1 and 2, formed on the opposite edges thereof, of the usual form and character and the teeth 1 are of greater pitch than the teeth 2, so that one pair of clippers may be provided with two complete sets of cutting edges of different character and size. Blade S, has a longitudinal and central depression 3, formed on the upper face thereof and a central rounded rib 4, extending longitudinally of the bottom thereof and in the center, said rib, as shown in Fig. 2, being adapted to touch a line coinciding with the beveled surfaces of the teeth 2, and being adapted to rest upon the surface of the body as the clippers are operated. 90

Movable blade M, is slightly shorter than the blade S, and is adapted to be reciprocably mounted thereon, a longitudinal depression 3' being formed in the bottom thereof, which corresponds with the depression 3 in the top of the blade S. The faces s and s' of blade S, and m and m' of blade M, are adapted to be held in slidable contact when the clippers are in operation and the movement of blade M over blade S is lifted and guided by means of lugs or pins 5, 5, on the blade S which extend upwardly through elongated slots 6, 6, formed in 110

blade M, said lugs and slots being alined longitudinally of said blades and said lugs being extended slightly above the upper side of the blade M, for a purpose herein-
5 after described.

A combined spacing and holding member H, which has its longest dimensions parallel with the cutting edges of the blades S and M, is mounted upon the upper side of
10 blade M and has a pair of rectangular de-pressions 7, 7, formed in the lower side thereof which are adapted to receive the upper ends of the lugs 5, 5, of blade S, the ends of said lugs serving to space the hold-
15 ing member H from blade M, so as to pro-
vide working clearance therebetween for easy operation of said blade.

The locking member L is circular in form and has a depending lug 8, formed on the
20 bottom thereof close to the periphery, which engages an aperture 9, formed in the move-
able blade M and the upper portion thereof has a plurality of notches 10, 10, etc., formed therein at regular intervals, four of
25 said notches being shown in the form of device illustrated and described. A pin 11
extends through a central bore 12, in the blade S through an elongated slot 13 in blade M, which is in communication with
30 the aperture 9 therein, and is extended sub-
stantially above and through a central bore 14 in the member L, said pin having a curved head 15 on the bottom with shoul-
ders thereon which engage the lower side
35 of blade S, as shown.

The main body member B is positioned on the upper side of member H and has a bore
40 16 extending therethrough, the sides thereof being extended in parallel rearwardly of the body, and a floor 17 being substantially ex-
tended rearwardly beyond the sides. A sec-
ondary body member b, has rearwardly ex-
tended handles 18 and 18' formed thereon and a flat portion 19, which rests upon and
45 serves as a cover for body member B. Mem-
ber b also has a boss 20 on the lower side thereof, which seats in the upper end of the bore 16 of member B, and a rear end closing member 21, which covers the rear end of member B and rests upon the floor 17 thereof and has a depending lug 22 on the lower edge thereof, which is adapted to engage a bore or seat 23 near the rear edge of floor 17.

A cross head C is slidably held transversely
50 of member B and between the rear side of said member and member 21 of member b. Said cross head has an inwardly extended lug 24 formed thereon which projects through an elongated opening 25 in the lower portion of the rear side of member B into the bore 16, a pin 26 being carried in a bore 27 in said lug which registers with and is adapted to seat selectively in the notches
55 10 of the locking member L. Opening 25 is of sufficient length to permit the transverse

movement of the cross head C, or rather the lug 24 thereon in said opening. The driving shaft D, is held in a bearing 29 formed on the member 19 of body member b, and the inner end of said shaft has a flange 30 there-
70 on adapted to seat in an elongated depres-
sion 31 in the cross head, and a forwardly ex-
tended end 32, which carries a roller 33, which operates in a vertical slot, or depres-
sion, 34, formed centrally of the cross head
75 C. A flexible shaft 35 may be suitably at-
tached to shaft D and housed in a flexible tube 36, as shown, for connecting the mech-
anism with a source of power.

All of the members described are firmly
held together for operation by means of a knurled nut 37 on the upper extended end of the retaining pin 11, and a flat operating member 38 is held in a notch 39 on the upper end of body member B, and has an operating end 40 exterior of said member and an inner end 41, with a slot therein through which the retaining pin 11 extends, the extreme end of said member 38 being adapted to seat in an annular groove 43 on the head 44, of the locking pin 26, the arrangement of said spring and pin being such that a slight pres-
sure on the operating end 40 of said spring will raise the pin 26 from its seat in the locking member L, and permit the manual
90 turning of the body members B and b, and cross head C for changing the position of the cutting edges of the blades S and M. A coil spring 45 is positioned between the operating member 38 and the boss 20 of member b and is adapted to be compressed when the outer end of member 38 is pressed, said spring serving to restore the pin 26 to a seat in one of the notches 10 of member L.

It will be understood that locking member L also serves to move the blade M by means of the lug 8, which seats in aperture 9, of blade M, and said locking member is oscil-
lated by means of the pin 26, in cross head C. The cross head, it will be apparent, is reciprocated by means of the eccentric roller 33, which seats in the vertical slot 34 thereof. Member H has a central bore 46, which rotatably receives and holds the member L for operation and said member H is held station-
110 ary with the blade S by means of the lugs and lug seats hereinbefore described.

When operating member 38 is depressed into contact with the periphery of body member B, the pin 26 will be raised out of engagement with member L, and the body members may be turned at right angles to their previous position relative to the blades S and M for changing the operating position of the blades, for it has been found to be convenient at times to make such a change for affording access to portions of the neck and head during a hair clipping operation.

The handles 18 and 18' have horns 48 and 49, respectively, formed thereon for position-
130

ing the hand of the operator properly on and for facilitating the holding of the handles during the operation of the mechanism. It will be understood that the handles 18 and 18' may be made separable and one of said handles provided with a lug for operating the cross head C in a manner similar to that employed in my former invention, hereinbefore referred to, and such a change in my 10 present device will provide a mechanism capable of operation by both power and manual means.

What I claim is:

1. A hair clipper having relatively stationary and movable blades, a supporting body therefor, an oscillatable element for operating said movable blade, a cross head movable in a plane at right angles to the axis of and for operating said oscillatable 20 element, and a rotatable element operably connected with and for moving said cross head.

2. A hair clipper comprising a hollow body, a handle detachably held on and forming a top and back for said body, a driving element rotatably supported on the back of said handle, cutting blades detachably held on said body, a cross head slidably supported in said body and adapted to be reciprocated in a plane transversely of said handle by said driving element, and means for operatively connecting said cross head with one of said blades, as set forth.

3. A hair clipper comprising a hollow body having a handle projecting therefrom, a guideway being provided in the front portion of said body, a reciprocable primary operating element held in said guideway, means for operating said element, relatively 40 stationary and movable cutters held on the bottom of said body, and an oscillatable secondary operating element interposed between and adapted to connect said reciprocating element with said movable cutter.

4. A hair clipper comprising a hollow body having a handle projecting therefrom, a guideway being formed in the front portion of said body, a reciprocable primary operating element held in said guideway, 50 means for operating said element, relatively stationary and movable cutters held on the bottom of said body, an oscillatable secondary operating element interposed between and adapted to connect said reciprocating 55 element with said movable cutter, and means for detachably holding all of said parts together.

5. A hair clipper comprising a hollow body having a handle projecting therefrom, 60 a guideway being formed in the front portion of said body, a reciprocable primary operating element held in said guideway, means for operating said element, relatively stationary and movable cutters held on the

bottom of said body, an oscillatable secondary operating element interposed between and adapted to connect said reciprocating element with said movable cutter, and means on said oscillatable element co-acting with means on said reciprocable element, whereby the relative positions of the cutting edges of said cutters may be changed, and the handle operatively disposed in planes paralleling and at right angles to the cutting edges of said cutters, selectively, at will. 65 70 75

6. A hair clipper comprising a hollow body, handles therefor, stationary and movable cutters, means for detachably holding said members together for use, means in said body for reciprocating said movable 80 cutter, means also in said body for locking said handle and said body in selected positions transversely of and parallel with the cutting edges of said cutters, and resilient means acting thereagainst for holding 85 said members in selected position during use, and having an extension from said body, whereby said members may be released for a change in position.

7. A hair clipper having a body, a stationary blade detachably held thereon, a movable blade interposed between said body and said stationary blade, a king pin extending through said blade and said body, an oscillatable element held on said pin and 95 having a depending portion engaging said movable blade, and a plurality of peripheral notches in said upper surface, an operating member for moving said oscillatable member, a pin vertically movable in said operating 100 member and adapted to engage said notches, means held on said body and engaging said pin for normally locking said members in operative position, and adapted to be manually operated for releasing said operating 105 member and said oscillating member.

8. A hair clipper having a body, a stationary blade detachably held thereon, a movable blade interposed between said stationary blade and said body, a king-pin 110 extending through said blade and said body, a rotatable element held on said pin and having a depending portion engaging said movable blade, means for operating said rotatable member, means held on the body 115 for locking said body against movement relative to said blades and adapted to be manually operated to permit the rotation of said body about said king-pin for adjusting the relative angle of the handle and the 120 cutting edges of said blades.

Signed at Los Angeles, Los Angeles county, California, this 12th day of March, 1919.

GEORGE A. LAFONTAINE.
